[57] **CLAIM**

The ornamental design for a combined spherical venturi blower head and ionizer for use in discharging static electricity, as shown and described.

DESCRIPTION

FIG. 1 is a front perspective view from above of the combined spherical venturi blower head and ionizer for use in discharging static electricity of my new design; FIG. 2 is a front perspective view from below thereof; FIG. 3 is a side elevational view of part A thereof, shown separately for clarity of illustration, the opposite side being a mirror image of that shown; FIG. 4 is a top plan view thereof; FIG. 5 is a rear elevational view thereof; and, FIG. 6 is a bottom plan view thereof.

FIG. 1

FIG. 2

FIG. 3

FIG. 4

FIG. 5

FIG. 6
